(57) **CLAIM**

The ornamental design for, an electric unicycle, as shown and described.

DESCRIPTION

FIG. 1 is a perspective view of an electric unicycle, showing my/our new design;

FIG. 2 is a front elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a rear perspective view illustrating the state of the article whose seat portion and footrests being unfolded thereof.

The rear side elevation view is a mirror image of the front elevation view.
